(57) **CLAIM**

What is claimed is the ornamental design for a stackable tray, as shown and described.

DESCRIPTION

FIG. 1 is a perspective view of a stackable tray showing a new design;

FIG. 2 is a front view of the stackable tray of FIG. 1;

FIG. 3 is a cross-section taken along line 3--3 of FIG. 2;

FIG. 4 is a side view of the stackable tray of FIG. 1;

FIG. 5 is a rear view of the stackable tray of FIG. 1;

FIG. 6 is a top view of the stackable tray of FIG. 1;

FIG. 7 is a bottom view of the stackable tray of FIG. 1;

FIG. 8 is a perspective view of another embodiment of the stackable tray of FIG. 1; and,

FIG. 9 is a perspective view of another embodiment of the stackable tray of FIG. 1.

The components of the display shown in broken lines illustrate portions of the stackable tray form no part of the claimed design.

1 Claim, 5 Drawing Sheets
